PUSHER

Stoddard B. Martin, Cleveland, Ohio; Central National Bank of Cleveland, executor of said Stoddard B. Martin, deceased, assignor to Margaret J. Martin

Application November 20, 1944, Serial No. 564,317

9 Claims. (Cl. 29—62)

1

This invention relates to pushers for automatic screw machines and the like.

Each spindle of an automatic screw machine ordinarily includes a rotating collet tube having a collet at its forward end which is arranged to be compressed radially to grip and rotate a bar of stock fed axially through the collet tube. At the end of each cycle of operations of the machine, the projecting end of stock is cut off from the bar, the collet opens, a new length of stock is fed forwardly, and the collet is again closed to grip the stock and repeat the cycle of operations. The stock is ordinarily fed forward by a pusher carried by a reciprocating pusher tube arranged between and coaxial with the collet tube and the stock.

To simplify the operations involved in changing the machine from one size stock to another it has been proposed to use interchangeable stock gripping pads removably mounted in a shell or the like carried on the end of the reciprocating pusher tube. Many difficulties have been encountered, however, in assembling the pads or bushings in the pusher shell so that they are properly held in place during operation of the machine and at the same time are quickly and easily removable.

The principal object of this invention is to overcome these difficulties and to mount removable and replaceable pads or bushings in a pusher shell in such a manner that they may be readily removed and replaced without the use of special tools and at the same time are securely held in place during operation of the machine.

Other objects of the present invention are to improve the construction of the removable bushing for a pusher of this type; to obtain both a resilient gripping action and a hardened non-resilient stock engaging surface in a one piece bushing; and to improve the bushing construction so as to facilitate its heat treatment to obtain a resilient portion and a hardened non-resilient stock gripping portion.

It is also desirable in pushers of this type to provide a one way stock gripping action so that sufficient grip can be obtained on the stock to insure accurate feeding and prevent rebounding when the stock strikes the stock gauge while minimizing the grip on the stock during the retracting stroke of the pusher so as to minimize wear and avoid scratching or marring the stock. Accordingly, further objects of this invention are to obtain a relatively light gripping action on the retracting stroke with an increased or substantially positive grip on the feeding stroke; and to

2

enable the tight gripping action to be prevented when desired to permit removal of the stock from the machine. Other objects and advantages of this invention will appear hereinafter.

5 In the accompanying drawings:

Fig. 1 is a side elevation of a pusher constructed in accordance with the present invention;

Fig. 2 is a cross section on the line 2—2 of Fig. 1;

10 Fig. 3 is a side elevation of the pusher shown in Fig. 1 with the parts arranged to prevent a tight gripping action on the forward stroke;

Fig. 4 is a side elevation on a reduced scale showing the bushing being removed from the pusher shell;

15 Fig. 5 is a side elevation of a modified form embodying the improved assembly feature of this invention without a wedging or tight gripping action; and

20 Fig. 6 is a side elevation of a further modification.

Referring to Figs. 1 to 4 of the drawings, the pusher includes a shell 10 arranged to be secured in any desired manner to the end of a pusher tube of an automatic screw machine. At its forward end the shell 10 is provided with oppositely disposed extensions 11 terminating in relatively short inwardly directed flanges 12. The extensions 11 are continuations of the body of the

25 shell and are relatively short circumferentially as illustrated in Fig. 2. Preferably the circumferential extent of each extension 11 is about 30° although this dimension can be increased in the smaller size pushers and decreased in the larger sizes if desired.

The shell 10 is formed internally with a bore 13 extended inwardly from the rear end of the shell and leaving a wall thickness corresponding to the thickness of the pusher tube to which the shell is secured. The extensions 11 are formed with a counterbore 14 of greater diameter than the bore 13 so that the thickness of the extensions 11 is less than the thickness of the remainder of the shell wall. The bores 13 and 14 are connected by a conical shoulder 15 forming a wedging surface on the shell.

The preferred form of bushing illustrated in Figs. 1 to 4 consists of a sleeve 16 split longitudinally from end to end at one point as indicated at 17. The sleeve 16 has an internal bore 18 of a size to fit a particular size of stock and at its forward end is formed with a counterbore 19 extending inwardly a short distance and forming 50 an integral ring 20 at the forward end of the

bushing of such size and wall thickness as to remain out of engagement with the stock.

The sleeve 16 is also formed with a plurality of slots 21 extending from the rear end of the bushing forwardly substantially to the counterbore 19 so that the bushing is formed into a plurality of segments integrally held together at their forward ends by the ring 20.

On its external surface the sleeve 16 is formed with a groove 22 extending from the ring 20 rearwardly to a shoulder 23. Beyond the shoulder 23 the sleeve is formed with a substantially cylindrical portion 24 of a diameter to fit snugly within the bore 14 and at its rear end the sleeve is formed with a conical portion 25 arranged to fit within and cooperate with the conical portion 15 within the shell.

The depth of the groove 22 with respect to the cylindrical portion 24 is equal to the depth of the flanges 12 on the extensions 11 so that the inner surfaces of these flanges 12 bear in the groove 22 while the cylindrical portion 24 bears in the bore 14. The axial length of the groove 22 is determined by the desired overlapping length of the conical surface 15 in the shell 10 and the conical surface 25 on the bushing so that when the bushing is pulled forward until the shoulder 23 engages the rear sides of the flanges 12 the rear end of the tapered portion 25 just clears the forward edge of the shell 10 between the extensions 11 as shown in Fig. 3.

The shell 10 is conveniently made from a solid tube by boring out the conical shoulder 15 and the bore 14, leaving metal of the initial thickness of the tube wall to form the flanges 12. The portions of the shell between the extensions 11 can then be milled away on both sides to the desired length and width. The extensions 11 are then given an inward set and the entire shell is spring tempered.

The bushing is made from metal capable of being given a spring temper and of being hardened, such as medium to high carbon steel. The bushing can be conveniently made from a length of tubing with an internal bore 18 equal to the diameter of the stock the bushing is to grip. After forming the counterbore 19, the split 17 and the slots 21 and turning the exterior surface, the entire bushing is given an inward set to partially close the split 17 and the rear portion of the bushing is given an inward set to partially close the slots 21. The bushing is then heat treated to harden the inner surface forming the bore 18 to the degree desired so as to form hardened wear resisting surfaces. The ring 20 is then annealed or drawn back to a spring temper, which can be readily accomplished in the usual manner without interfering with the hardness of the stock engaging portions of the bushing.

The bushing and shell may be readily assembled by simply placing the ends of the flanges 12 against one side of the groove 22 immediately adjacent the shoulder 23 and pressing the bushing laterally into axial alignment with the shell 10. This action is permitted because the combined length of the cylindrical portion 24 and the conical portion 25 on the bushing do not substantially exceed the length of the extensions 11 behind the flanges 12. To facilitate the spreading of the extensions 11 the bushing may be tipped as shown in Fig. 4 and then pivoted into axial alignment with the shell.

Means may also be provided to prevent gripping engagement of the conical surfaces 15 and

25 when desired. As illustrated in Figs. 1 to 3 a split band 28 may be snapped over the bushing 16 in the groove 22 and positioned at the forward end of the groove 22 against the integral ring 20. The band 28 is provided with a pair of relatively long extensions 29 adapted to substantially abut the shoulder 23 so as to hold the band in place and with a pair of shorter extensions terminating in shoulders 30 adapted to be brought into engagement with the outer ends of the flanges 12 as shown in Fig. 3 to prevent the bushing 16 from moving axially into the shell 10 and thus prevent gripping engagement between the conical surfaces 15 and 25.

In normal operation the stock S is intermittently rotated in one direction when it is gripped by the collet carried by the collet tube surrounding the pusher tube and shell 10. The bushing 16 by reason of its resilient grip on the stock tends to rotate with the same and to transmit this rotation to the shell 10. The extensions 29 are formed with lateral shoulders 31 arranged to engage the adjacent ends of the flanges 12 when the stock is rotated in the normal direction of rotation of the machine. The lateral shoulders 31 extend in an axial direction so as not to interfere with the relative reciprocation of the bushing 16 and the shell 10. When it is desired to prevent gripping engagement between the conical surfaces 15 and 25 the stock may be pushed forward and rotated in the direction opposite to its normal direction of rotation so as to bring the shoulders 30 over the outer ends of the extensions 11, in the position shown in Fig. 3, so that the stock can be pulled rearwardly out of the pusher without bringing the conical surfaces 15 and 25 into wedging engagement.

It is to be understood that the shoulders 30 and 31 may be integral with the bushing 16 or may be formed in any other desired way, but the mounting of these shoulders on the spring ring 28 is preferred since this permits all of the machining on the outer surfaces of the bushing to be done by turning and the ring 28 may be stamped out from sheet metal easily and inexpensively. It will also be understood that the ring 28 and the shoulders 30 and 31 may be omitted when desired.

In operation the pusher tube to which the shell 10 is attached is advanced or moved to the left, as seen in Fig. 1, when a new length of stock is to be fed forwardly. The inward set given to the bushing and the spring temper of the ring 20 provides a resilient grip of the bushing on the stock so that the bushing remains in place while the shell moves to the left, bringing the conical surfaces 15 and 25 into engagement. These surfaces wedge the bushing sections inwardly against the stock, providing a tight grip during the feeding motion and preventing rebounding when the stock strikes the gauge. On the retracting stroke the shell 10 moves to the right as seen in Fig. 1. During this motion the shell slides over the bushing until the flanges 12 engage the shoulder 23 and pull the bushing to the right over the stock against the friction provided by the spring grip of the bushing. When no stock is disposed within the bushing the latter collapses to the extent of its initial inward set. The flanges 12, however, remain in snug engagement with the bottom of the groove 22 by reason of the inward set and spring temper given to the extensions 11. Thus the bushing

cannot escape from the shell when there is no stock within the bushing.

In the form shown in Fig. 5 the bushing is assembled in the pusher in the same manner previously described but operates only with a spring grip and without the wedging action on the forward stroke. The shell 110 is substantially the same as the shell 10 illustrated in Figs. 1 to 4, and is provided with the extensions 111 and flanges 112. The bushing 116, however, is formed with a groove 122 which needs to be only slightly greater in axial extent than the axial length of the flanges 112. Behind the groove 122 the bushing is provided with a substantially cylindrical portion 124 of a diameter to fit the bore 114 in the extensions 111. The axial length of the cylindrical portion 124 may be substantially equal to the combined axial lengths of the cylindrical portion 24 and the conical portion 25 shown in Figs. 1 and 3. The construction, method of assembly and operation of the bushing 116 are otherwise the same as described in connection with Figs. 1 to 4 inclusive.

A further modified form of bushing is illustrated in Fig. 6. In this figure the shell 10, extensions 11 and flanges 12 may be the same as illustrated in Figs. 1 and 3. The bushing 216 is formed externally with a cylindrical portion 224 and a conical portion 225 arranged to fit the conical portion 15 in the shell 10. In advance of the cylindrical portion 224 the bushing is formed with a shoulder 223 and a conical groove 222, preferably having a smaller degree of taper than the conical surfaces 225 and 15. The conical surface 222 terminates at the rear end of the integral ring 220. In this embodiment on the forward stroke of the pusher shell the conical surface 15 in the shell engages the conical surface 225 on the bushing and increases its grip. At the same time the inner surfaces of the flanges 12 ride up on the conical surface 222 providing a further increase of the grip of the bushing by reason of the inward set and spring tension of the extensions 11. However, before the conical surfaces 15 and 225 have been wedged together with sufficient force to lock the bushing on the stock the forward edges of the flanges 12 engage the shoulder at the rear end of the ring 220 and prevent further tightening of the wedging surfaces. With this arrangement it is unnecessary to provide means to hold the wedging surfaces out of engagement when it is desired to withdraw a bar from the pusher since the increased gripping force provided by the wedging surfaces is limited by the engagement of the flanges 12 with the rim 220. Thus a tighter grip is provided on the feeding stroke than on the retracting stroke but the grip never tightens sufficiently to lock the pusher to the stock.

Although preferred embodiments of the invention have been described in considerable detail it will be understood that many variations and modifications thereof can be resorted to within the scope of the invention. For example, the limitation of the gripping force in the embodiment shown in Fig. 6 may also be used in the arrangement shown in Figs. 1 to 4 inclusive with a single set of wedging surfaces in place of the abutments provided by the spring ring. Similarly the quick assembly feature may be used with other forms of bushings and the improvements in the bushing itself may be used with other kinds of pusher shells.

I claim:

1. A pusher comprising a shell having extensions projecting axially from its forward edge,

said extensions being formed with rearwardly facing abutment shoulders on their inner surfaces, a bushing adapted to grip stock to be fed fitting between said extensions, said bushing being formed with forwardly facing abutment surfaces adapted to engage said rearwardly facing abutment shoulders, the length of said bushing from said forwardly facing surfaces to the rearward end of said bushing being substantially no greater than the length of said extensions from said rearwardly facing abutment shoulders to the forward edge of said shell, and the circumferential spacing between at least two adjacent edges of said extensions being such that said bushing may be assembled in said shell by being snapped laterally into position between said extensions.

2. A pusher comprising a shell having extensions projecting axially from its forward edge, said extensions being formed with rearwardly facing abutment shoulders on their inner surfaces, a bushing adapted to grip stock to be fed fitting between said extensions, said bushing being formed with forwardly facing abutment surfaces adapted to engage said rearwardly facing abutment shoulders, said projections being tensioned inwardly so as to engage resiliently with said bushing forwardly of said forwardly facing abutment surfaces, the length of said bushing from said forwardly facing surfaces to the rearward end of said bushing being substantially no greater than the length of said extensions from said rearwardly facing abutment shoulders to the forward edge of said shell and the circumferential spacing between at least two adjacent edges of said extensions being such that said bushing may be assembled in said shell by being snapped laterally into position between said extensions.

3. A pusher comprising a shell, a bushing within said shell arranged to grip stock to be fed, cooperating wedging surfaces on said bushing and said shell arranged to increase the grip of said bushing on said stock when said shell moves forwardly with respect to said bushing, cooperating abutments on said shell and bushing adapted to engage and prevent relative movement of said shell and bushing in the opposite direction, said shell being formed with an extension projecting axially from the forward edge thereof and a forwardly facing abutment on the forward end of said extension, and a ring surrounding said bushing and having a rearwardly extending abutment member, said member being adapted, in one angular relation of said ring and said shell, to pass said extension, and in another angular relation of said ring and said shell, to engage said forwardly facing abutment and prevent engagement of said wedging surfaces.

4. A pusher comprising a shell, a bushing within said shell arranged a grip stock to be fed, operating wedging surfaces on said bushing and said shell arranged to increase the grip of said bushing on said stock when said shell moves forwardly with respect to said bushing, cooperating abutments on said shell and bushing adapted to engage and prevent relative movement of said shell and bushing in the opposite direction, said shell being formed with an extension projecting axially from the forward edge thereof and a forwardly facing abutment on the forward end of said extension, and a spring band surrounding and gripping said bushing and having a rearwardly extending abutment member, said member being adapted, in one angular relation of said band and said shell, to pass said extension, and, in another angular relation of said band and said shell, to

engage said forwardly facing abutment and prevent engagement of said wedging surfaces.

5. A pusher comprising a shell, a bushing within said shell arranged to grip stock to be fed, the rear end of said bushing being formed with a wedging surface, a cooperating wedging surface on the interior of said shell, said surfaces being arranged to increase the grip of said bushing on said stock when said shell moves forwardly with respect to said bushing, cooperating abutments on said shell and bushing adapted to engage and prevent relative movement of said shell and bushing in the opposite direction, said shell being formed with an extension projecting axially from the forward edge thereof and a forwardly facing abutment on the forward end of said extension, and a ring surrounding said bushing and having a rearwardly extending abutment member, said member being adapted, in one angular relation of said ring and said shell, to pass said extension, and, in another angular relation of said ring and said shell, to engage said forwardly facing abutment and prevent engagement of said wedging surfaces.

6. A pusher comprising a shell having a pair of circumferentially spaced resilient axial extensions at its forward end, said extensions carrying rearwardly facing abutment shoulders on their inner surfaces, a bushing adapted to grip stock to be fed, said bushing having an annular forwardly facing abutment surface adapted to contact said rearwardly facing abutment shoulders to pull said bushing rearwardly when said shell moves rearwardly with respect to the stock, the circumferential spacing between said extensions on at least one side being such that said bushing may be assembled in said shell, by being snapped laterally into position between said extensions, and said annular forwardly facing abutment surface being of sufficient circumferential extent to engage said rearwardly facing abutment shoulders in all angular positions of said bushing with respect to said shell.

7. A pusher comprising a shell having a pair of circumferentially spaced resilient axial extensions at its forward end, said extensions carrying rearwardly facing abutment shoulders on their inner surfaces, a bushing formed to resiliently grip stock to be fed, said bushing having an annular forwardly facing abutment surface adapted to contact said rearwardly facing abutment shoulders to pull said bushing rearwardly when said shell moves rearwardly with respect to the stock, said extensions being bent inwardly and constructed to engage resiliently with said bushing in advance of said annular abutment surface, the circumferential spacing between said extensions on at least one side being such that said bushing may be assembled in said shell, by being snapped laterally into position between said extensions, and said annular forwardly facing abutment surface being of sufficient circumferential extent to engage said rearwardly facing

abutment shoulders in all angular positions of said bushing with respect to said shell.

8. A pusher comprising a shell having extensions projecting axially from its forward edge, said extensions being formed with rearwardly facing abutment shoulders on their inner surfaces, a bushing adapted to fit between said extensions and to grip stock to be fed, said bushing being formed with forwardly facing abutment surfaces adapted to engage said rearwardly facing abutment shoulders, said projections being tensioned inwardly so as to engage resiliently with said bushing forwardly of said forwardly facing abutment surfaces, the forward edge of said shell and the rearward end of said bushing being formed with cooperating abutment surfaces, the length of said bushing from said forwardly facing surfaces to the rearward end of said bushing being less than the length of said extensions from said rearwardly facing abutment shoulders to the forward edge of said shell, and the circumferential spacing between at least two adjacent edges of said extensions being such that said bushing may be assembled in said shell by being snapped laterally into position between said extensions.

9. A pusher comprising a shell having a pair of circumferentially spaced extensions projecting axially from its forward edge, said extensions being formed with rearwardly facing abutment shoulders on their inner surfaces, a bushing adapted to fit between said extensions and to grip stock to be fed, said bushing being formed with forwardly facing abutment surfaces adapted to engage said rearwardly facing abutment shoulders, the forward edge of said shell and the rearward end of said bushing being formed with cooperating abutment surfaces, the length of said bushing from said forwardly facing surfaces to the rearward end of said bushing being less than the length of said extensions from said rearwardly facing abutment shoulders to the forward edge of said shell, and the circumferential spacing between at least two adjacent edges of said extensions being such that said bushing may be assembled in said shell by being snapped laterally into position between said extensions.
